WIRE LINE SWIVEL

Felix L. Pivoto, Liberty, Tex.

Application November 4, 1935, Serial No. 48,201

3 Claims. (Cl. 255—25)

The invention relates to a swivel of the type used in supporting a string of pipe during the drilling of wells by the rotary method and is particularly directed to a swivel through which a wire line may be passed, if desired, and which may also be closed in order that fluid pressure may be applied to the pipe supported by the swivel.

In well drilling operations by the rotary method where a string of pipe is turned by the rotary mechanism it is necessary to support the string of pipe and to apply fluid pressure thereto in order to maintain a circulation of the drilling fluid during the drilling operation. Various types of equipment have now been devised which may be lowered through the drill stem in order to obtain samples of the formation and for various other purposes, and it is the practice to lower these instruments by means of a cable or wire line. It is desirable, of course, to lower such instruments through the drill pipe without disconnecting the swivel which supports the pipe and the present invention has been devised with a view of providing a swivel which is convenient for such an operation.

It is one of the objects of the invention to provide a swivel having a passage therethrough which may be closed if desired.

Another object of the invention is to provide a swivel having a combination fluid and implement passage therethrough.

Another object of the invention is to provide a swivel head with a closure cap which may be used to completely close the top of the swivel.

Another object of the invention is to provide a swivel cap which is arranged to accommodate a wire line so that various implements may be raised or lowered through the drill pipe and swivel.

Another object of the invention is to provide a swivel through which various instruments may be lowered into the well bore without removing the swivel from its connection with the drill pipe.

Other and further objects of the invention will be readily apparent when the following description is considered in connection with the accompanying drawing, wherein:

Figure 1 is a vertical sectional view of a swivel showing the wire line passing through the swivel while the swivel is connected to the string of pipe in the well.

Figure 2 is a side elevation at right angles to the view of Figure 1 and showing the top of the swivel closed with a plug so that fluid pressure

may be applied when no wire line is passing through the swivel.

The drill stem by which the bit or other equipment is rotated is indicated generally at 2 and is provided with an upstanding threaded box 3. This box is arranged to receive a threaded pin member which may be the swivel or the next section of pipe. In Figure 1 the pin member 4 of the swivel is connected into the box 3 and in this manner the swivel 5 is connected to the drill pipe. The swivel includes a housing 6 which carries the pin 4 and is provided with spaced side members 7 which converge together in the head 8.

Positioned inside of the housing 6 is a sleeve 10 which fits into the passage 11 passing through the lower end 12 of the housing 6. This sleeve 10 is sealed against leakage from the passage 11 by means of the packing 14, which is held in place by a gland 15 near the lower edge of the sleeve 10. The side windows 16 between the arms or brackets 7 permit access to the gland 15 so that it may be adjusted to form a proper seal. A lock ring 15' is arranged to hold the gland in any set position.

This sleeve or spindle 10 carries near its upper end an outstanding flange 18 which is received within a chamber 19 in the top 8 of the swivel. While a single flange 18 on the spindle 10 is shown in Fig. 1, it is obvious that any suitable number of such flanges may be provided to receive the thrust between the spindle 10 and the body 8. Positioned above and below this flange 18 are the anti-friction bearings 20 so there will be relatively little friction upon the rotation of the housing with respect to the spindle. A cap 21 holds the bearings and the spindle in place in the top of the housing. A grease inlet 21 is provided so that lubricant can be injected into the bearings 20. When the drill stem rotates the housing 5 of the swivel will rotate with it and the spindle 10 will remain stationary because it is connected to the head 30 which forms part of the swivel.

The head 30 is specially constructed with a passage 31 therein, the lower portion of which is enlarged and threaded at 32 to receive the upper end 33 of the spindle or sleeve 10. A gooseneck 34 projects from one side of the head 30 and is threaded at 35 to receive the mud line 50 by which fluid is forced through the passage 36 in the gooseneck and down through the passage 11 in the spindle to maintain a circulation of fluid during the drilling operation, it being understood that the pipe 2 is rotated while the fluid

is being circulated. In order to suspend the pipe, swivel and the head 30, a pair of outstanding ears 37 have been provided on the head 30 and these ears receive the bails 39 which are carried by a suitable hoisting mechanism.

- 5 With swivels of this general type heretofore the passage 31 extended laterally into the passage 36 of the gooseneck but did not extend upwardly through the top of the swivel, and thus when it is desired to insert a tool or wire line into the string 10 of pipe 2 it was necessary to disconnect the entire swivel and support the pipe 2 by slips in the rotary table or in any other desired manner. When the swivel was disconnected, however, circulation could not be maintained. In the present swivel 15 attention is directed to the fact that the passage 31 extends upwardly above the branch passage 36 and is threaded at 40 to receive a plug 41. This plug is preferably made in two halves so that they can be positioned about a cable or wire line 20 42. These two halves will then be bolted together by bolts passing through the opening 43 therein and the threaded lower end 44 thereof can then be screwed into the threaded portion 40 in the head 30. If a tight seal is desired, the packing 25 45 may be compressed by the gland 46 so that a complete seal may be maintained about the wire line 42. If, however, the wire line is to be moved up and down, the gland 46 will not be tightened but movement of the line 42 will be permitted. This is desirable when a tool is being raised or 30 lowered in the drill stem.

When the drilling operation is to be resumed and there is no wire line passing into the drill 35 pipe, then the plug 50 shown in Figure 2 will be inserted in the threads 40 of the head 30. A suitable handle 51 is provided to turn this plug into position. In this manner the upper end of the passage 31 is completely closed and any desired fluid pressure may be exerted on the 40 inside of the drill pipe.

Broadly the present invention contemplates a modification of the present swivel so that it will be adapted to receive a wire line with a very slight alteration such as removing the plug 50 and 45 inserting the wire line 42 having the plug 41 positioned thereon so that the rotation of the pipe, the circulation of drilling fluid or the manipulation of the wire line tools may be carried on either independently or simultaneously if desired.

50 What is claimed is:

1. A swivel for use in well drilling operations to support the drill pipe and adapted to accommo-

date wire line operated tools therein comprising a body, a spindle therein, bearings supporting said body on said spindle, means to support said spindle, a vertical passage through said spindle, a head thereon having a passage in alignment with said spindle passage and a plug normally closing said passage but removable for the insertion and removal of tools through said swivel which are manipulated by a wire line passing through said swivel.

2. A rotary swivel including a body having a central bore, said body having a chamber within an enlarged portion adjacent its upper end, an enlargement in said bore below said chamber, a cup within said body above the enlargement thereon, a spindle having a flange within said cup, packing about said spindle within the enlarged bore, a gland about said spindle above said packing, an opening in the wall of said enlargement to admit a tool for said gland and to permit egress of fluid leaking past said gland, a nut threadably secured in the cup about said spindle, thrust bearings between the flange and the cup and nut, respectively, a support head fixed to said spindle including ears to suspend said swivel, a gooseneck extending laterally from said head, a passage through said spindle and support head, the passage through said gooseneck leading into said spindle passage, and a wire line passing through said swivel and having a plug thereon to close the top of said head, said plug comprising half sections fixed about the wire line.

3. A swivel for use in well drilling operations to support a drill pipe and adapted to accommodate wire line operated tools therein comprising a body having a central bore and a chamber within an enlarged portion thereof, an enlargement in said bore below said chamber, a cup within said body above said chamber, a spindle extending into said bore and having a flange within said cup, packing and a gland therefor about said spindle within the enlarged bore, an opening in the wall of the enlargement to admit a tool for said gland, a nut threadably secured in the cup about said spindle, thrust bearings between the flange and the cup and nut respectively, a supporting head rigidly secured to said spindle and having a passage in alignment with the spindle passage, and a plug normally closing said passage but removable for insertion and removal through said swivel of the tools which are manipulated by a wire line passing through said swivel.
